Primary Examiner — Elizabeth Albert(74) *Attorney, Agent, or Firm* — Wolf, Greenfield & Sacks, P.C.; Randy J. Pritzker(57) **CLAIM**

The ornamental design for hole punch, as shown and described.

DESCRIPTION

FIG. 1 is a top, front, left side perspective view of a first embodiment of the hole punch;

FIG. 2 is a front elevational view of the embodiment of FIG. 1;

FIG. 3 is a rear elevational view of the embodiment of FIG. 1; FIG. 4 is a right side elevational view of the embodiment of FIG. 1;

FIG. 5 is a left side elevational view of the embodiment of FIG. 1; and,

FIG. 6 is a top plan view of the embodiment of FIG. 1. The broken lines shown showing part of the hole punch that are unclaimed are included for illustrative purposes of illustrating portions that form no part of the claimed design.
